UNITED STATES PATENT OFFICE.

BERGER STOCKFLETH, OF BERRIEN SPRINGS, AND FREDERICK W. BURGER, OF NILES, MICHIGAN, ASSIGNORS TO CLARK TRUCTRATOR COMPANY, OF BUCHANAN, MICHIGAN, A CORPORATION OF MICHIGAN.

MEANS FOR HANDLING ROLLS OF PAPER.

Application filed April 21, 1924. Serial No. 708,055.

To all whom it may concern:

Be it known that we, BERGER STOCKFLETH, a citizen of the United States, and a resident of Berrien Springs, in the county of 5 Berrien and State of Michigan, and FREDERICK W. BURGER, a citizen of the United States, and a resident of Niles, in the county of Berrien and State of Michigan, have invented certain new and useful Improvements 10 in Means for Handling Rolls of Paper, of which the following is a specification, reference being had to the accompanying drawings.

The rolls of paper from which newspapers 15 are printed are very heavy and they have to be handled with considerable care to avoid liability of damage to the layers of paper, and particularly is that the case in connection with their insertion in and removal 20 from the freight cars into which they are loaded for transportation from their place of manufacture. In such cars they are usually placed on end close together, and it is desirable, and common practice, to lift 25 them bodily from the car without turning them over on their sides because such turning them over into position so that they might be rolled is apt to damage the outer layers at their edge, and, also, the outer 30 layers might be damaged by contact with irregularities in the surfaces that they are rolled over, &c. In order to lift them straight up and move them in that condition out of a car it has been common to 35 employ an expanding clutch device that is inserted into the hollow core that each such roll is wound upon and then, by means of a suitable tool, causing an expansion of the device into such tight frictional engagement 40 with the core that the frictionally-engaging device will not slip with relation to the core when an upward pull is given on a rod or other connection that extends from such clutching or clamping device out beyond the 45 upper end of the roll. By reason of that tight frictional engagement of such a device with a roll core it has been possible to effect the desired vertical lifting of these heavy rolls, but such means are at times objectionable 50 owing to the tendency of the core itself to move longitudinally of the roll and thus cause more or less of the inner layers of the roll of paper to move with the core, the effect of such movement being that the

central portion of the upper end of a roll 55 will be bulged outwardly,—the extent of such outward bulging varying in different rolls according to the character of the paper and other causes. Such bulging is highly objectionable in that it not only renders the 60 paper more readily subject to damage while in its rolled form and also renders it difficult to stack such rolls when placed one upon another end to end, but the web as it is drawn rapidly into a printing press cannot move into the press with that precision 65 that is essential to the production of the large number of newspapers that are to be printed from a roll of paper.

It is the leading object of our invention 70 to provide means for attachment to a heavy roll of paper that will enable the roll to be lifted vertically from a standing-on-end position without causing any such bulging at the upper end of the roll or without imposing any lateral pressure upon the core that would tend to injure the core itself or cause any disturbance of the smooth surfaces of the inner layers of the papers due to the pressure of any device in the core that was forced into strong frictional engagement 75 with the core. Another object of the invention is to so construct the means by which a roll is adapted to be engaged for lifting purposes that one member of such means will at all times lie opposite and in contact with a substantial portion of that end of the roll that will be the lower end while the roll is being transported or in storage and will serve as a base for the roll 80 to rest upon, and, in case the floor of the car or storage place should be damp or badly soiled, will protect the paper by holding the roll off of such floor. A still further object 85 of the invention is to construct the roll-engaging means so that that member thereof that projects into an end portion of one roll-core will be adapted to receive and house a projecting end portion of a suspending rod that engages with the similar roll-engaging means in the core of another roll, whereby such rods may constitute a part of the equipment furnished with each roll, and yet such rods will not, by reason of projecting 90 beyond one end of each roll, respectively, offer any obstruction to the piling of one roll upon another end to end, as is the desirable practice in press-rooms and other 95 100 105

places. These objects we accomplish by the construction shown in the drawing and hereinafter specifically described. That which we believe to be new will be set forth 5 in the claims.

In the drawing:—

Fig. 1 is a perspective view of a device embodying the invention;

Fig. 2 is a vertical central section through 10 a roll of paper, and showing in elevation the device of Fig. 1 applied thereto, there being also shown in dotted lines a portion of another roll that is provided with a like device, which latter roll is supported on the 15 upper end of the other roll; and

Fig. 3 is a detail, being an enlarged vertical section through the device, some of the parts thereof being partly broken away.

Referring to the drawing,—5 indicates a 20 flat plate, preferably annular in shape to conform to the shape of the end of a roll of paper with which it is to be used and against one end of which roll said plate is adapted to lie. A roll of paper, such as is 25 used for the printing of newspapers, is shown in dotted lines and is indicated by A. As shown the plate 5 lies closely against that end of the roll that will normally be the lower end of the roll during 30 its transportation or storage, and, as will be evident, such plate will by holding the roll out of actual contact with a floor aid in preventing damage to the roll in the event that such floor should be damp or 35 soiled. The plate may be of any desired diameter but preferably will be of materially less diameter than the roll, as when of such less diameter it is found to extend over a sufficient portion of the end surface 40 of the roll to provide not only a stable base for the roll to rest upon when on the floor of a car or other place, but what is of greater importance furnishes a surface of sufficient area for the roll to rest upon without 45 disturbing the even windings of the several layers composing the roll when the plate and the roll are moved upward by a pull applied at the axis of the plate, as hereinafter described.

50 Formed centrally through the plate 5 is a hole 6, and surrounding such hole and projecting from that surface of the plate that lies against the roll is a comparatively short hollow cylindrical plug 7 that is adapted 55 to project into the adjacent end of the hollow core a of the roll. Such cylindrical plug member is to be firmly united to the plate in any suitable manner, or, indeed, the two parts may be formed integral with each 60 other. The member 7 is preferably to be made of a size to snugly fit within the core so as to be normally held therein by frictional contact with the wall of the core for it is contemplated as the most desirable way 65 of making use of the invention that the

parts 5 and 7 shall remain attached to a roll from the time such roll is shipped out of the paper mill to the time when the roll is to be placed on the usual roll-holder preparatory to feeding the web of paper to a 70 printing-press. As herein shown, the end of the plug-like member is provided with a fixed head 8 through the central portion of which is formed a tapped opening 9. A rod 10 that has a screw-threaded end portion adapted to engage the head 8 by being screwed into the opening 9 is provided as a means to be engaged by any suitable lifting mechanism. As shown, this rod projects beyond the upper end of the roll, and 75 in such projecting end portion is formed an eye 11 which may be of elongated shape as in the drawing, or otherwise, to adapt it to be engaged by a hook or finger or other suitable element of the lifting mechanism 80 that may be employed for the lifting operation.

While the suspending rod 10 is preferably detachably connected with a plug member 7 and therefore one such rod might be 90 successively used in connection with a number of paper rolls that were to be lifted and moved out of a car, or otherwise, yet as such use of a single rod in connection with different rolls would in many instances be very 95 inconvenient we prefer and recommend that each roll as shipped be provided with its own rod properly connected to the plug 7 in the core of that roll, because thereby a car load of rolls can be handled in the least 100 time and with the least amount of labor. The projection of the rod in each roll at all times beyond that end of the roll that is uppermost is not a bar to the placing of rolls upon each other end to end, as is commonly 105 done while the rolls are in storage or are held in a press-room, because of the fact that the projecting portion of the rod that is carried by a lower roll will extend into and be housed by the hollow plug in the lower 110 end of the core of the next higher roll. While, therefore, so far as the lifting function is concerned the plugs may vary as to their length, and the extent to which the 115 rods project may also vary, yet in view of the desirability of stacking the rolls one upon another end to end, it is important that the length of plug and the extent of projection of the rod be such as to permit of the desired end to end stacking of the 120 rolls.

While any suitable elevating mechanism for effecting a lifting of the rolls may be employed it is contemplated that such lifting be performed by mechanism carried by 125 or connected with a small tractor such as are commonly employed in and about warehouses, railroad stations and other places. With such an elevating mechanism having a suitable projecting element adapted to ex- 130

tend over a roll and engage the eye 11 of the rod 10 that projects from such roll it will be evident that when power is applied to vertically move such extending element 5 the roll will be lifted off of the floor of the car or other place on which it had rested and can, while so suspended, be transported to and deposited at the place desired.

By our invention we provide cheap, simple and effective means for enabling a heavy roll of paper to be handled and at all times maintained in an upright position, and which, by reason of the manner of its association with a roll, will neither cause injury 10 to the core of the roll or to any of the layers of paper that compose the roll, and that also will not cause a distortion of the roll by bulging it out at one end. The parts of the device are capable of being used many times 15 by being returned from time to time to the makers of the rolls, as is common practice in connection with the roll cores.

What we claim as our invention and desire to secure by Letters Patent, is—

25 1. Means for handling and lifting a roll of paper comprising in combination a member adapted to extend across and lie in contact with one end of the roll, a plug projecting centrally from one face of said member and adapted to project into the hollow central part of the roll, and suspending means connected at one end with said plug and adapted for attachment at its other end to a lifting device.

35 2. The combination with a roll having a hollow center, of means for handling and lifting said roll comprising a plate in contact with one end of the roll, a plug connected with said plate and projecting into the hollow center of the roll, and suspending means in said center of the roll connected with said plug.

45 3. The combination with a roll having a hollow center, of means for handling and lifting said roll comprising a plate in contact with one end of the roll, a plug connected with said plate and projecting into the hollow center of the roll, and a suspending rod in said center of the roll connected at one end with said plug and projecting at its other end beyond the other end of the roll.

55 4. The combination with a roll having a hollow center, of means for handling and lifting said roll comprising a plate in contact with one end of the roll, a plug connected with said plate and projecting into the hollow center of the roll, and a suspending rod in said center of the roll adjustably connected at one end with said plug and projecting at its other end beyond the other end of the roll.

65 5. The combination with a roll having a hollow center, of means for handling and lifting said roll comprising a plate in con-

tact with one end of the roll, said plate having a central opening therethrough, a hollow plug connected with said plate around said opening and projecting into the hollow center of the roll, a suspending rod in said 70 center of the roll, and means for connecting the inner end portion of said rod with the inner end portion of said plug.

6. The combination with a roll having a hollow center, of means for handling and 75 lifting said roll comprising a plate in contact with one end of the roll, said plate having a central opening therethrough, a hollow plug connected with said plate around said opening and projecting into the hollow 80 center of the roll, a suspending rod in said center of the roll, and means for detachably and adjustably connecting the inner end portion of said rod with the inner end portion 85 of said plug.

7. The combination with a roll having a hollow center, of means for handling and lifting said roll comprising a plate in contact with one end of the roll, said plate having a central opening therethrough, a hollow 90 plug connected with said plate around said opening and projecting into the hollow center of the roll, a head secured in the inner end portion of said plug, and a suspending 95 rod in said center of the roll connected at its inner end portion with said head.

8. The combination with a roll having a hollow center, of means for handling and lifting said roll comprising a plate in contact with one end of the roll, said plate having a central opening therethrough, a hollow 100 plug connected with said plate around said opening and projecting into the hollow center of the roll, a head secured in the inner end portion of said plug, said head having a screw-threaded opening therethrough, and a suspending rod having threaded engagement with said opening in the head.

9. The combination with a roll having a hollow center, of means for handling and lifting said roll comprising a plate in contact with one end of the roll, said plate having a central opening therethrough, a hollow 110 plug connected with said plate around said opening and projecting into the hollow center of the roll, a head secured in the plug, a suspending rod in said center of the roll having its inner end portion connected with said head and having its other end portion projecting beyond the other end of the roll, said head in the plug being located at a distance from the end of the roll that it is adjacent to to receive and house the projecting portion of a suspending rod carried by another roll when such other roll is placed in end to end relation with the first-mentioned roll.
